His Attorney.

UNITED STATES PATENT OFFICE

JACOB M. ENDERS, OF SCHENECTADY, NEW YORK

COMBINED ANTRATTLER AND WINDOW-LATCHING DEVICE

Application filed December 27, 1929. Serial No. 416,850.

The object of my invention is to provide a simple and inexpensive unitary structure which may be manufactured in a single operation by either casting or stamping it from metal, is adapted to prevent rattling of a window and at the same time secure it in any desired position, thus preventing movement in either direction.

For an understanding of the invention, reference should be had to the following description taken in connection with the accompanying drawing and its novel features will be pointed out with particularity in the appended claims.

15 In the drawing, Figure 1 is a top or plan view of the device; and Figure 2 is a side elevation of Figure 1.

Referring to the drawing, 10 is a flattened non-circular body member provided with a pivot opening 11 therein for the purpose of attaching the device to the window sash 12. This may be done by any well known means, such as a screw 15 shown in Figure 2. The shape of the flattened member is shown in the drawing as being a rectangle having concave arcuate sides 19 with the outer portions 13 curved, it being substantially I shaped in plan. The outer portions 13 are rounded transversely and are of uniform bevel throughout their entire width to form knife edges which are adapted to fit tightly under the window stop 14 by a wedging action when the device is in a closed position. Intermediate the pivot opening 11 and the beveled edges 13 there are two upwardly projecting members 16 triangularly shaped in cross section, as shown in Fig. 2. These projecting members 16 serve as a rigid handle for the device and may be made integral with the body member 10, or it may be a separate piece of metal rigidly secured to the body member in any well known manner to form a unitary structure. The working surfaces of said projecting members 16 have contacting surfaces 18 which are contiguous to the outer beveled ends 13 for effectively engaging the window stop 14.

50 In operating the device, the projecting members 16 are rotated away from the vertical position so that one of the contacting

edges is brought into working relationship with the window stop 14 to latch the window sash in any desired position. During this movement the beveled or knife edge 13 simultaneously cams the sash of the window frame against the stop 14, wedging the sash in its frame to prevent any rattling thereof.

With a device of this type applied to each side of a window sash, it may be effectively latched in any position by operating one of the devices in a direction opposite to the other. With such an arrangement, one of said devices prevents the opening and the other the closing of the window.

What I claim as new and desire to secure 65
by Letters Patent by the United States is:

1. A combined window latch and anti-rattler device adapted to be fastened to a window sash, comprising a pivoted non-circular flattened body member, said member having a beveled knife shaped end for engagement with the window sash and its stop to prevent rattling of the window when in position, and an upwardly projecting member having a contacting surface adapted to simultaneously engage the window stop to latch the window in any desired position.

2. As an article of manufacture, a combined window latch and antirattler adapted to be fastened to a window sash, comprising a pivoted body member that is I shaped in plan and provided with wedge-shaped bevelled ends rounded transversely and of uniform bevel throughout their entire width and adapted to be inserted between the window sash and stop to prevent rattling of the sash, and upwardly extending projecting members on said body provided with contacting surfaces contiguous to said bevelled edges and arranged so that one of said projecting members will contact with said window stop to simultaneously latch the window in a set position when transverse movement of the sash is prevented by its contiguous wedge-shaped end.

Signed at Schenectady, in the county of Schenectady and State of New York, this 21st day of December, 1929.

JACOB M. ENDERS.
